ROLLER CHART

Melville E. Foster, Minneapolis, Minn.

Application August 17, 1949, Serial No. 110,691

4 Claims. (Cl. 40—85)

1

This invention relates to a roller chart unit and comprises an improvement upon the construction shown in my co-pending application, Serial #25440, filed May 6, 1948.

It is an object of the present invention to provide a roller chart assembly including a supporting structure having improved means for holding a spring roller rotatably therein and means for releasably locking the roller shaft relative to the roller support.

The above and other objects and advantages of my invention will more fully appear from the following description made in connection with the accompanying drawings, wherein like reference characters refer to similar parts throughout the several views and, in which:

Fig. 1 is a front elevational view of an embodiment of the invention showing it mounted on the underside of a shelf.

Fig. 2 is an enlarged view partially in section and with the central portions broken away.

Fig. 3 is an enlarged fragmentary sectional view through one end of the roller support.

Fig. 4 is a section taken approximately on the line 4—4 of Fig. 3.

Fig. 5 is a section similar to Fig. 4 and taken through the other end of the roller support.

Fig. 6 is an enlarged detail partially in section of the roller rod rotating and locking knob.

Fig. 7 is a section taken approximately on the line 7—7 of Fig. 6, and

Fig. 8 is an enlarged section taken approximately on the line 8—8 of Fig. 2.

The roller support includes a housing 9 having a front panel 10 and a top 11. The ends of these panels are turned to overlap each other, providing end plate portions 10a and 11a. The end plate portions 10a are also bent outwardly at 10b to provide attachment clips when the device is placed against a vertical supporting surface. The top panel 11 may be provided with suitable holes not shown to accommodate attachment screws when the device is mounted as shown in Fig. 1.

The left hand end of the housing 9 is illustrated in Figs. 3 and 4. The end plate portion 10a is provided with a circular aperture 12 and the end plate portion 11a with a slot 13 which extends upwardly from the lower edge of said portion 11a and terminates at the circular opening 12. A suitable rivet 14 connects the end plate portions 10a and 11a.

The other end of the housing 9 is formed by extensions of the panels 10 and 11 similarly to the end plate portions 10a and 11a, except that

2

both of these end plate portions 10d and 11d are provided with slots 15 extending inwardly from their lower edges. These end plate portions are suitably firmly connected by a rivet 16.

At either side of the coincident slots 15 in the right hand end plates are circular apertures 17 which serve as anchoring apertures for a roller shaft locking arrangement to be described below.

In Fig. 2 there is shown an elongated cylindrical member 18 which constitutes a roller. It has end plugs 19 and 20 through which are extended a roller rod or shaft 21. Lying around the shaft 21 and within the cylindrical roller 18 is a torsion spring 22 having one end 23 extending between the plug 19 and the cylinder 18 and then bent over at the outer side of the plug. The other end of the spring 22 is bent upon itself as at 24 and seated in a hole which is formed through the roller rod 21 adjacent the right end thereof.

The right hand end of the roller rod 21 extends a considerable distance beyond the end of the housing 9, and is provided with a knob 25. This knob is shown in detail in Figs. 6 and 7. It has a cup shaped flange 26 forming a part thereof and from opposite sides of the flange extend hook-like members 27 which lie parallel to the roller rod 21. The hook-like members 27 are receivable in the apertures 17 which pass through the right hand end of housing 9. The hooks 28 on the member 27 are adapted to lie inside of the end plate portion 10d and said hook portions 18 are so disposed that the spring 22 will yieldably maintain them in a hooked position. In order to release them the knob 25 is turned very slightly against the twisting spring 22 to dislodge the hooks 28 so that the members 27 can be entirely withdrawn from the openings 17 and the roller rod 21 can then be rotated. When the rod is thus rotated and the roller cylinder 18 is held stationary, the spring 22 can be wound to give it any desired increased tension to properly roll a chart such as the chart 29 shown in Fig. 1.

The spring 22 is also stretched somewhat longitudinally of the rod 21 so that the hook-like elements 27 on the knob 25 will be further held in the openings 17 in the right hand end plate portion 10d.

The roller assembly can be readily removed from the housing 9. When the knob 25 is turned slightly and pulled outwardly longitudinally of the axis of the rod 21, said rod and the entire roller assembly can be removed. The rod 21 at its right hand end can be slipped out of the slots 15 in the end plates 10d and 11d and the left hand

end of the rod 21 can then be pulled longitudinally from the circular opening 12 in the left hand end plate portion 10a.

When the roller is re-mounted in the housing 9 the guide slot 13 in the left hand end plate portion 11a will readily guide the end of the roller rod 21 into registration with the circular aperture 12 in the end plate portion 11a. The right hand end of the assembly can then be anchored by placing the hook units 27 in their respective apertures 17 in the right hand end portion 10d.

The features brought out herein are directed to means for facilitating tightening of the spring 22 and also to readily removing the roller assembly from the housing so that new charts can be placed thereon and the roller easily replaced. The units can be made very compact and its assembly is dependable even though the structure is comparatively simple.

It will, of course, be understood that various changes may be made in the form, details, arrangement and proportions of the various parts without departing from the scope of my invention.

What I claim is:

1. In a roller chart, a roller support including an end plate with a roller shaft guide recess formed therein, a roller shaft extending through and rotatable in said recess, said shaft having limited axial movement relative to said end plate and having a fixed end member having a hook-like portion extending toward said end plate, and said end plate having an aperture in which said hook-like portion is removably received.
2. The structure in claim 1 and said roller having a spring connected thereto to yieldably urge it axially in one direction and further to yieldably maintain said hook-like portion in its end plate aperture.
3. In a roller chart, a roller support, including

an end plate having a roller shaft guide slot therein, a roller including a cylindrical member and a shaft extending therethrough and rotatable relative thereto, a coil spring about said shaft and connected between said shaft and said cylindrical member, said spring being under tension longitudinally of said shaft, said shaft having its end extending through said guide slot, said end plate having an aperture therein adjacent said guide slot, and an end member fixedly mounted on said shaft at the outer side of said end plate, said end member having a hook-like portion extending toward said end plate and said hook-like portion being removably received in said second mentioned aperture and yieldably retained therein by said coil spring.

4. In a roller chart, a roller support including a top wall, a first end wall, and a second end wall, said second end wall having a recess formed therein and extending inwardly from one of its side edges, said recess being adapted to rotatably receive therein a roller shaft for guiding purposes only, said second end wall also having cooperative roller shaft engagement means spaced from said recess.
